UNITED STATES PATENT OFFICE.

PERCY H. THOMAS, OF MONTCLAIR, NEW JERSEY, ASSIGNOR, BY MESNE ASSIGNMENTS, TO COOPER HEWITT ELECTRIC COMPANY, OF HOBOKEN, NEW JERSEY, A CORPORATION OF NEW JERSEY.

OUTFIT FOR ALTERNATING-CURRENT VAPOR-LAMPS.

1,079,379.

Specification of Letters Patent.

Patented Nov. 25, 1913.

Application filed September 27, 1905. Serial No. 280,255.

To all whom it may concern:

Be it known that I, PERCY H. THOMAS, a citizen of the United States, and resident of Montclair, county of Essex, State of New Jersey, have invented certain new and useful Improvements in Outfits for Alternating-Current Vapor-Lamps, of which the following is a specification.

In supplying customers with outfits which include alternating current vapor lamps, it is found that there is difficulty in securing anything like uniformity in the outfit required for circuits carrying different voltages and for meeting different conditions in the lamp circuit itself. At the same time, it tends to economy of manufacture to standardize the outfit as much as possible and to satisfy the various conditions of actual service. It would, for example, be a substantial improvement in the art to provide means whereby a standard outfit could be supplied for voltages ranging from 240 down to 100 volts without modifying the size of the voltage absorbing ballast employed as a means of regulation and without changing substantially the size of the auto-transformer which may be introduced between the supply circuit and the lamp circuit. When a ceiling outfit is employed, that is, an inclosing case located near a ceiling which may be of combustible material, this uniformity in the size and general style of the apparatus is particularly desirable, if only effective means are provided for reducing the energy losses in the auto-transformer.

It is the object of the present invention to provide means whereby all the desirable features mentioned above may be combined and the desired results successfully obtained.

The attempt has already been made to accomplish some of the objects above mentioned by locating the above mentioned ballast or other regulating device on the line side of the auto-transformer; but it is found that such an arrangement is not adequate to accomplish all the results aimed at herein and this invention is intended to remedy the defects of prior systems of distribution relating to alternating current vapor lamps in the particulars pointed out in this specification. In some instances it may be desirable to operate a number of lamps from the same auto-transformer, each with its own ballast;

but this cannot be accomplished by placing 55 the ballast on the line side of the transformer.

In carrying out the present invention I locate the ballast or other regulating device in the lead of one or more of the positive 60 electrodes of the alternating current lamp and whenever it is found necessary I arrange the connections of the auto-transformer so that there is an unbalancing of the electro-motive-forces applied in the several 65 alternations between the negative electrode and the positive electrodes in such a manner that equal quantities of energy will be absorbed by the energy storing or maintaining coil which always forms a part of 70 the apparatus, as is now well known. In other words, the voltage applied between the negative electrode and every positive electrode in whose lead a ballast is included is enough higher than the voltage applied between the negative electrode and any other positive electrode or electrodes to compensate for the additional resistance of the ballast. Furthermore, to secure the minimum 75 size of auto-transformer, when the supply 80 voltage is normally less than that which is necessary between the positive electrodes, the supply is applied to such a portion of the auto-transformer as to allow the energy to pass substantially directly from line to 85 lamp when traversing the ballast.

By virtue of the described arrangement, the ballast serves to limit the amount of current flowing through the lamp at any instant, as at starting, when conditions are 90 favorable for establishing a short-circuit between positive electrodes.

My invention will be understood by reference to the accompanying drawings in which—

Figures 1 and 2 are diagrammatic views 95 of circuits suitable for carrying out my invention.

In Fig. 1, 1 is an auto-transformer supplied from mains, 2 and 3. The lamp to be 100 operated is shown at 4 and the same is supplied with positive electrodes, 5 and 6, and with a negative electrode, 7. The connections to the positive electrodes extend from the respective terminals of the auto-transformer 1 and the negative electrode 7 is connected through a choke-coil 8, to an intermediate point, 9, of the transformer. The line

wire 2 is also connected to an intermediate point, 10, of the transformer. In the lead to the positive electrode 5 a ballast, 11, such as is frequently used for controlling varying voltages and vapor pressure variations in direct current lamps of this character, is introduced, the lead to the other positive electrode being generally unimpeded. One suitable form of such ballast consists of an iron wire placed in hydrogen gas and operated at or near red heat. The particular form of the ballast utilized, is, however, not a part of the present invention. It will be seen that voltage applied to the circuit including the ballast 11 is greater than that applied to the unimpeded circuit. By a proper adjustment of the connections to the auto-transformer, this distortion of the balance between the two sides of the circuit may be made to affect equally the maintaining or sustaining coil 8 so that in operation the unbalancing of the applied electro-motive-forces will result in a uniform action upon the two circuits, resulting in a steady operation of the lamp 4.

In Fig. 2 I illustrate a somewhat different mode of unbalancing the circuits, the main difference being that the line conductors 2 and 3 are connected to the terminals of the auto-transformer and the adjustment made by the connections on the lamp side of the circuit. This arrangement is particularly suited to cases where the line supply is naturally greater than the voltage to be delivered to the lamp.

The principles of the invention herein disclosed are obviously applicable not only to single phase but polyphase lamps as well.

I claim as my invention:—

1. The combination with a single phase alternating current source, a vacuum device comprising a hermetically sealed and completely exhausted container, positive electrodes and a vaporizable reconstructing cathode therein and an alternating current transformer winding for supplying said device, connections from the negative electrode to an intermediate point of the winding and from the positive electrodes to points on the winding on opposite sides of said intermediate point, of a current regulating device in the lead to one positive electrode, the relative position of the points of connection in the winding being such as to cause a voltage to be impressed upon the positive electrode whose lead contains the said regulating de-

vice, which is relatively higher than the voltage impressed upon the other positive electrode.

2. The combination with an alternating supply winding and a vacuum device comprising an exhausted container, anodes and a vaporizable cathode, adapted to rectify alternating currents from said supply windings, of connections for supplying current through said device from both waves of the supply and means for deriving from said supply unequal voltages whereby unequal currents tend to flow from alternate waves of the source and an inductance in the circuit of the rectified current to steady and equalize the current flow produced by said unequal voltages.

3. The combination with an apparatus adapted to utilize separately both waves of an alternating current supply, an auto-transformer connected with said supply and a controlling device traversed by current derived from one wave of said supply, of means for passing energy through said auto-transformer with a small ratio of transformation from said supply to said apparatus through said controlling device and means for passing energy with a larger ratio of transformation from the other wave of the supply in the original direction through said apparatus, thus reducing the transformation losses of the energy supplied through said controlling device.

4. In a system of electrical distribution wherein an alternating current vapor lamp is supplied from a single-phase source, a transformer, connections from the transformer to one of the positive electrodes of the lamp through a current regulating device, connections from another portion of the transformer to the other positive electrode and means whereby the transformer is unbalanced so that the voltage supplied through the positive electrode connected with said regulating device shall be enough higher than the voltage applied to the other positive electrode to compensate for the resistance of the said device.

Signed at New York, in the county of New York, and State of New York, this 25th day of September A. D. 1905.

PERCY H. THOMAS.
